UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,556, dated March 3, 1891.

Application filed February 6, 1891. Serial No. 380,515. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a new design for a cane or umbrella handle. A is the shank, and extends upwardly, terminating in a crook B on the one hand and a point D on the other, the said parts B and D being separated by a band of ornamentation C. The sides of the shank A may be ornamented by ribs F, as shown. The lower

part of the shank A is mounted by a band E, the upper portion of which may be highly ornamented.

20 The handle may be formed of any suitable material.

Having now described my design, what I claim as new, and desire to secure by Letters Patent, is—

25 The design for cane or umbrella handles, substantially as herein described and shown.

In testimony of which invention I have hereunto set my hand.

HENRY O. SCHMIDT.
